LONG OR SHORT LINE ASSEMBLY
ELEVATOR STOP

Wilbert J. Swatzell, El Dorado, Ark.

Application December 28, 1944, Serial No. 570,154

15 Claims. (Cl. 199—18)

1

My invention relates to improvements in typographical casting machine stops, and particularly to a safety device for application to and use upon "Linotype" and "Intertype" and like typographical composing and line casting machines.

An object of this invention is to provide an attachment for "Linotype" and other type casting machines which is designed to prevent a line casting machine from sending an assembled line of matrices into the machine when the line is either too long or too short.

A further object is to provide an automatic stop in the nature of an assembling elevator lock which will prevent sending in long or tight lines as well as short or loose lines of matrices as these are assembled for movement to casting positions, so that the thus improperly assembled line will not be sent into the machine for casting.

Another object is to provide stop means automatically operating as the matrices are assembled so that if the assembled line is too short or too long the machine stops before the line of matrices of improper length is elevated to the position from which it goes to the casting mechanism, so that possible damage to the matrices and assembled space bands or other damage such as spouting of metal will be avoided.

Still another object is to so construct and arrange the parts that the stop mechanism and the operating means therefor can be quickly and readily embodied in connection with standard parts of such machines, and without material structural alterations.

Yet another purpose is to provide stop means having the parts thereof actuated by normal functional operations of the machine, and which stop means will consequently be substantially automatic in its operation and functioning.

Another object is to provide stop means that can be fitted upon and can be mounted in connection with the usual parts of a machine, and which provides for adjustment and setting of the parts so that the machine can be operated in usual and normal manner, and without actuation of the automatic stop.

With the above and other objects in view, some of which will be apparent to those skilled in the art, and others of which are inherent in the use and operation of my improved structure, this invention includes certain novel features of construction and arrangements and assemblies of parts which will be hereinafter set forth in connection with the drawings and then pointed out in the claims.

In the drawings:

Figure 1 is a fragmentary front perspective view showing parts of a type casting machine with my invention applied thereto.

2

Fig. 2 is a view in perspective showing an assembler slide roll bracket with the main portions of this invention applied thereto.

Fig. 3 is a perspective view looking from the rear and showing the parts illustrated in Fig. 2.

Fig. 4 is a fragmentary view similar to Fig. 3 showing parts in different operative relation.

Fig. 5 is a transverse sectional view substantially on line 5—5 of Fig. 2.

Fig. 6 is a fragmentary perspective view showing certain operating parts encased.

Fig. 7 is a perspective view taken at a different angle and better showing the case or shield structure.

Fig. 8 is a perspective view, looking from the rear, and showing the assembler slide as this would appear when detached from the machine and when fitted with the detachable lug.

Fig. 9 is a transverse sectional view substantially on line 9—9 of Fig. 8.

Fig. 10 is a view in edge elevation of the assembler slide with the lug detached.

The disclosure in Figure 1 of the drawings is intended to represent only fragmentary portions 25 of a typographical casting machine, such as the "Linotype" or "Intertype" machines, and the portion thus illustrated discloses the assembling elevator and assembler slide and the assembler slide roll bracket of an ordinary machine, with 30 which parts my present invention is particularly concerned.

The assembling elevator is adapted to receive the matrices and space bands, and to elevate these to other portions of the machine where 35 they are held in position to receive molten metal from which a slug or line of type is cast. This assembling elevator is generally indicated at 1, in Figure 1 of the drawing, and the assembler slide roll bracket is indicated at 2, the roll thereof being shown at 3. An assembler slide 4 is mounted for substantially horizontal movement within the machine, in the usual manner. In fact, the parts of the machine as particularly described, and all other parts and operating features, can be of 40 substantially standard form and construction in their general shape.

The parts of my invention are assembled upon and cooperate with the assembler slide roll bracket 2 and the assembler slide 4, and the stop structure to be hereinafter more fully described 45 is intended and adapted to prevent movement of the assembling elevator if a line of assembled matrices and space bands as supplied thereto be too short or too long. In other words, the device 50 stops the too long or too short assembled line in the machine where no damage can result to either the matrices or the space bands.

The assembler slide roll bracket 2 is cut away or reduced on its rear side, as at 5, as best shown 55 in Figs. 3 and 4, and a lock lever 6 is pivotally

mounted on a shoulder screw 1, or other suitable pivoting means so that this lever will be freely swingable. The lower end of the lever is provided with a locking lug 8, and is preferably cut away or otherwise made sufficiently light that the upper end 9 of the lever will overbalance and will consequently swing the lower end of the lever to move the locking lug 8 to project beyond the side of the assembler slide roll bracket 2, and a stop is provided at 10 to limit the projection of the locking lug end 8.

The stop 10 normally limits outward swinging movement of the lower end of the lever 6, and an eccentric cam 11 is rotatably mounted on the rear side of the assembler slide roll bracket 2 and is adapted to be turned through the medium of operating lever 12 on the forward side of the bracket, and consequently readily available to the machine operator, to interpose the cam to limit swinging movement of the lower end of the lever 6 so that the locking lug end 8 will not project beyond the side of the assembler slide roll bracket 2. This eccentric cam 11 is provided to permit adjustment and setting of the parts so that the locking end 8 of the lever 6 will be held in a position where it will be ineffective to lock or stop movement of any part, and the eccentric cam 11 and setting lever 12 are provided to permit the operator to render this stop means inoperative, so that the machine can be operated in usual manner, when desired.

At its upper end 9, the lever 6 is offset so that it will be substantially aligned with the roll 3, and consequently the assembler slide 4, and this offset end is freely swingable below and immediately adjacent to the lower edge of the assembler slide 4. The end 9 of lever 6 has a screwthreaded opening therethrough, and a contact member 13, in the form of an elongated screw, is fitted through the opening with the end 14 thereof projecting as an adjustable contact portion.

The assembler slide 4 is cut away or otherwise reduced on its rear side to provide a recess 15, which extends longitudinally of the elongated assembler slide bar in that portion above the swinging end of the lever 6, and the assembler slide has a plurality of openings 16 bored or otherwise formed therein and extending substantially transversely of the bar from the lower edge, these openings being substantially in communication with the recess 15. An operating lug 17 has pins 18 thereon adapted to be fitted through openings 16 in the assembler slide 4 to depend from the lower edge of the assembler slide in substantially the manner shown in Figs. 1 and 8. A detent spring 19 is provided within the recess 15 to engage with the pins 18 and thus retain the detachable lug 17 in position. This spring 19 can hold the pins 18 through frictional engagement, or slight tooth formations can be provided on the pins, as indicated at 20 in Fig. 9.

When the detachable lug 17 is fitted in position upon the assembler slide 4, and this slide is moved endwise, and to the left as the parts are shown in Fig. 1, the contact end 14 of the screw 13 carried by the upper end 9 of lever 6 will be engaged by the end face of the lug and in consequence the lever 6 will be swung sufficiently to swing the lower end of the lever and withdraw the locking lug 8 from its extended position.

The assembling elevator is provided with a projection 21, shown in Fig. 1, which is engaged by the stop lug 8 when this lug is in the extended position, and consequently when the lever 6 is

swung to a position to withdraw the stop lug 8, the assembling elevator can be moved upwardly. The detachable lug 17 can be adjusted by placing the pins 18 thereof in different openings 16 as formed in the lower edge of the assembler slide 4, to thus accomplish settings of the stop parts for lines of different lengths, and the screw 13 can be turned to adjust the length of extension of the contact end 14 for more minute adjustments.

If too few matrices are assembled in one line, and if the line of assembled matrices and space bands is consequently too short or too loose, the assembler slide 4 will not go far enough to bring lug 17 into engagement with the contact end 14 and consequently the lever 6 will not be swung sufficiently to withdraw the stop or locking lug 8 of the lower end of the lever from a position where it will permit passage of the projection or shoulder 21. If the line be of proper length, or too long, the lug 17 will engage contact 14 and the lever 6 will be swung to withdraw the locking lug end 8 to permit movement of the assembling elevator to advance the assembled line of matrices and space bands to the casting position.

The above described parts will provide an automatic stop to prevent advancing a line that is too short or too loose; but, my invention also contemplates employment of these same parts to prevent the advancing of an assembled line of matrices and space bands that is too long or too tight. Where the assembled line is too long, the lug 17 engages the contact 14 and swings the lever 6 to move the lower end thereof a distance somewhat greater than is necessary to merely withdraw the stop or locking lug end 8 to the position where it will clear the projection or shoulder 21, and I employ this greater movement of the lower end of the lever to actuate a second stop means.

This second stop means is adapted to interpose a stop that will prevent movement of the assembling elevator to advance an assembled line that is too long or too tight. A supporting bracket 22 is mounted upon and extends laterally from the edge of the lower portion of the assembler slide roll bracket substantially below the position of the lever 6, and this bracket has a slide 23 thereon positioned to be engaged by the lower end of the lever 6 upon the increased or greater swinging movement of this lever, as just above described. A lever 24 is swingably mounted by a pin or other suitable pivoting means, upon the bracket 22 with one end thereof engaging the outer end of the slide 23, and a spring 25 is provided to normally exert resilient force to draw the contacting end against the slide and consequently move the slide to its innermost position. The assembler slide roll bracket 2 has an opening 26 bored or otherwise formed substantially obliquely therethrough, as best shown in Fig. 5, so that a locking bolt member 27 can be slidably mounted through this opening with its bolt end substantially in a position to be extended to engage the projection or shoulder 21 of the assembling elevator. The bolt member 27 is extended at its inner end and is pivotally connected with the swinging end of the lever 24, as at 28.

With the second stop mechanism as described, movement of the assembler slide 4 in a relation to advance a long or tight assembled line of matrices and space bands will cause the lug 17 to swing lever 6 to bring the lower end thereof into contact with the slide 23, in consequence of which the lever 24 will be swung to actuate the locking bolt 27 to extend the locking end

thereof into a position in the path of the projection or shoulder 21 of the assembling elevator, and therefore this assembling elevator cannot be moved to advance the long or tight line. To provide for adjustments of the parts, an adjusting screw 29 is provided on the lever 24 with its end adjustably bearing against the slide 23.

By removing the detachable lug 17, the assembler slide 4 is free to move without affecting in any way the lever 6, and consequently when the operator desires to release or render inoperative the stop means, he will not only operate the handle 12 to interpose the eccentric cam 11 to engage the lever 6 and withdraw the locking lug 8, but will also remove this detachable lug 17. When the automatic stop means is thus rendered inoperative, the machine can be used in the usual manner.

To protect the operating parts of the second stop means, a shield or cover 30, best illustrated in Figs. 6 and 7, can be provided. This cover or shield is preferably removable so that access can readily be had to the parts, but it will be seen that the end of the cover or shield is open to permit access to be had to the adjusting screw 29 for adjustments of the parts.

The screws 13 and 29 provide for adjustments to give desired clearances for the two stops, and if desired, nuts 34 and 34' can be provided on one or both of these screws to hold or retain the adjustments thereof. As stated, since the assembler slide 4 has a plurality of sockets or openings 16 therein, the detachable lug 17 can be adjusted to desired positions to accommodate different lengths of lines to be set by the machine.

From the foregoing it will be seen that I have provided stop means adapted for use with "Linotype," "Intertype" or other line casting machines, which is of simple and inexpensive construction, and which will operate efficiently to stop the mechanism if the assembled matrices and space bands be either too long or too tight, or too short or too loose, and which will operate to prevent advancing of the long or short line to the casting position, thus protecting the machine and the parts before the assembled matrices have been advanced to a point where damage will be likely to be done to the matrices and possibly to the machine.

While I have herein shown and described only certain specific embodiments of my invention and have suggested only certain possible modifications, it will be apparent to those skilled in the art that many changes and variations can be made in the design and construction and assembly of the parts, and in the manner of operating and of rendering the parts operative and inoperative, without departing from the spirit and scope of my invention as set forth in the appended claims.

I claim:

1. Typographical casting machine stops embodied with an assembling and casting machine having an assembling elevator and an assembler slide comprising, a projection on the assembling elevator, a lever swingably mounted adjacent to said assembling elevator and having one swinging end thereof normally interposed to engage the projection and stop movement of said assembling elevator, a second stop means disposed to be contacted by the end of said lever when excessive movement is imparted thereto by a too long line to extend said second stop means to

engage the projection, and a lug on the assembler slide engaging with the opposite end of said swinging lever.

2. Typographical casting machine stops embodied with an assembling and casting machine having an assembling elevator and an assembler slide comprising, a projection on the assembling elevator, a lever swingably mounted adjacent to said assembling elevator and having one swinging end thereof normally interposed to engage the projection and stop movement of said assembling elevator, a second stop means disposed to be contacted by the end of said lever when excessive movement is imparted thereto to extend said second stop means to engage the projection, a lug on the assembler slide engaging with the opposite end of said swinging lever, and means to retain said lever in position with the end thereof withdrawn from stopping position.

3. Typographical casting machine stops embodied with an assembling and casting machine having an assembling elevator and an assembler slide comprising, a projection on the assembling elevator, a lever swingably mounted adjacent to said assembling elevator and having one swinging end thereof normally interposed to engage the projection and stop movement of said assembling elevator, a second stop means disposed to be contacted by the end of said lever when excessive movement is imparted thereto to extend said second stop means to engage the projection, a lug on the assembler slide engaging with the opposite end of said swinging lever, and means to retain said lever in position with the end thereof withdrawn from stopping position, said lug being detachable from the assembler slide to thus avoid movement of the lever.

4. Typographical casting machine stops embodied with an assembling and casting machine having an assembling elevator and an assembler slide comprising, a projection on the assembling elevator, a lever swingably mounted adjacent to said assembling elevator and having one swinging end thereof normally interposed to engage the projection and stop movement of said assembling elevator, a second stop means disposed to be contacted by the end of said lever when excessive movement is imparted thereto by a long line to extend said second stop means to engage the projection, and a lug on the assembler slide engaging with the opposite end of said swinging lever, said lug being adjustably mounted on said assembler slide to accommodate the stop to lines of different lengths.

5. An automatic stop for type line casting machines having an assembling elevator and an assembler slide comprising, lock means normally resisting movement of said assembling elevator, means detachably carried by said assembler slide functioning upon movement of a line of matrices of normal length to release said lock means, and manually settable means actuatable to render said lock means inoperative whereby upon detachment of the means on the assembler slide the machine can be used in normal manner.

6. An automatic stop for type line casting machines having an assembling elevator and an assembler slide comprising, a projection on the assembling elevator, stop means carried by said machine and normally interposing a stop lug against said projection to stop movement of said assembling elevator, a detachable lug carried by said assembler slide adapted to engage and render inoperative said stop means when a line of

matrices of normal length is moved into position to be carried by said assembling elevator, said lug being adjustable upon said assembler slide for lines of different lengths, and spring means holding said lug detachably in position.

7. An automatic stop for type line casting machines having an assembling elevator and an assembler slide comprising, a projection on the assembling elevator, stop means carried by said machine and normally interposing a stop lug against said projection to stop movement of said assembling elevator, a detachable lug carried by said assembler slide adapted to engage and render inoperative said stop means when a line of matrices of normal length is moved into position to be carried by said assembling elevator, said lug being adjustable upon said assembler slide for lines of different lengths, means holding said lug detachably in position, and means on said machine manually actuatable to render said lock means inoperative.

8. A typographical casting machine stop for machines having a movable assembling elevator and a movable assembler slide comprising, a projection on the assembling elevator, a swingable lever having a locking lug at one end mounted on parts of the machine with the locking lug end normally occupying a position contacting said projection and resisting movement of said assembling elevator, said assembler slide being provided with a plurality of openings, and a detachable lug having pins thereon received in the openings of the assembler slide and adjustably and detachably holding said lug in position on said assembler slide to engage a part of said lever when the assembler slide is actuated to move a line of matrices.

9. A typographical casting machine stop for machines having a movable assembling elevator and a movable assembler slide comprising, a projection on the assembling elevator, a swingable lever having a locking lug at one end mounted on parts of the machine with the locking lug end normally occupying a position contacting said projection and resisting movement of said assembling elevator, said assembler slide being provided with a plurality of openings, a detachable lug having pins thereon received in the openings of the assembler slide and adjustably and detachably holding said lug in position on said assembler slide to engage a part of said lever when the assembler slide is actuated to move a line of matrices, said lever being movable beyond the extent required to withdraw the locking lug from locking position, and a second stop means actuated by excess swinging movement of said lever to interpose a stop in the path of movement of the projection on the assembling elevator.

10. A typographical casting machine stop for machines having a movable assembling elevator and a movable assembler slide comprising, a projection on the assembling elevator, a swingable lever having a locking lug at one end mounted on parts of the machine with the locking lug end normally occupying a position contacting said projection and resisting movement of said assembling elevator, said assembler slide being provided with a plurality of openings, a detachable lug having pins thereon received in the openings of the assembler slide and adjustably and detachably holding said lug in position on said assembler slide to engage a part of said lever when the assembler slide is actuated to move a line of matrices, said lever being movable beyond the extent required to withdraw the locking lug from locking position, a second stop means ac-

tuated by excess swinging movement of said lever to interpose a stop in the path of movement of the projection on the assembling elevator, and means to adjust and vary the extent of movement of each of said stop means.

11. A typographical casting machine stop for machines having a movable assembling elevator with an assembler roller bracket adjacent thereto and a movable assembler slide adapted to be actuated to move a line of assembled matrices and space bands to the assembling elevator comprising, a projection on the assembling elevator, a lever swingably mounted in its middle portion on said bracket in overbalanced relation with one end normally swung by gravity to interpose said end as a stop lug contacting said projection and preventing movement of the assembling elevator, said lever having a portion thereof disposed adjacent said assembler slide, and a lug on said assembler slide engageable with the adjacent portion of said lever upon movement of the assembler slide to withdraw the locking lug end from the locking position when a line of matrices of normal length is advanced to the assembling elevator.

12. A typographical casting machine stop for machines having a movable assembling elevator with an assembler roller bracket adjacent thereto and a movable assembler slide adapted to be actuated to move a line of assembled matrices and space bands to the assembling elevator comprising, a projection on the assembling elevator, a lever swingably mounted in its middle portion on said bracket in overbalanced relation with one end normally swung by gravity to interpose said end as a stop lug contacting said projection and preventing movement of the assembling elevator, said lever having a portion thereof disposed adjacent to said assembler slide, and a lug on said assembler slide engageable with the adjacent portion of said lever upon movement of the assembler slide to withdraw the locking lug end from the locking position when a line of matrices of normal length is advanced to the assembling elevator, said locking lug being adjustably mounted upon the assembler slide for adjustment to accommodate different lengths of lines to be cast by the machine.

13. A typographical casting machine stop for machines having a movable assembling elevator with an assembler roller bracket adjacent thereto and a movable assembler slide adapted to be actuated to move a line of assembled matrices and space bands to the assembling elevator comprising, a projection on the assembling elevator, a lever swingably mounted in its middle portion on said bracket in overbalanced relation with one end normally swung by gravity to interpose said end as a stop lug contacting said projection and preventing movement of the assembling elevator, said lever having a portion thereof disposed adjacent said assembler slide, a lug on said assembler slide engageable with the adjacent portion of said lever upon movement of the assembler slide to withdraw the locking lug end from the locking position when a line of matrices of normal length is advanced to the assembling elevator, said lever being capable of swinging movement in excess of the movement required to withdraw the locking lug end from locking position, and a second lock means actuated by excessive swinging movement of said lever and engageable with the projection.

14. A typographical casting machine stop for machines having a movable assembling elevator with an assembler roller bracket adjacent thereto

and a movable assembler slide adapted to be actuated to move a line of assembled matrices and space bands to the assembling elevator comprising, a projection on the assembling elevator, a lever swingably mounted in its middle portion on said bracket in overbalanced relation with one end normally swung by gravity to interpose said end as a stop lug contacting said projection and preventing movement of the assembling elevator, said lever having a portion thereof disposed adjacent said assembler slide, a lug on said assembler slide engageable with the adjacent portion of said lever upon movement of the assembler slide to withdraw the locking lug end from the locking position when a line of matrices of normal length is advanced to the assembling elevator, said lever being capable of swinging movement in excess of the movement required to withdraw the locking lug end from locking position, a second lock means actuated by excessive swinging movement of said lever and engageable with the projection, and manually actuatable means carried by said bracket operable to hold said lever in position with the locking lug end thereof in inoperative position whereby when the detachable lug on the assembler slide is removed the machine can be used and operated in normal manner.

15. A typographical casting machine stop for machines having a movable assembling elevator with an assembler roller bracket adjacent thereto and a movable assembler slide adapted to be actuated to move a line of assembled matrices and space bands to the assembling elevator comprising, a projection on the assembling elevator, a lever swingably mounted in its middle portion on said bracket in overbalanced relation with one

end normally swung by gravity to interpose said end as a stop lug contacting said projection and preventing movement of the assembling elevator, said lever having a portion thereof disposed adjacent said assembler slide, a lug on said assembler slide engageable with the adjacent portion of said lever upon movement of the assembler slide to withdraw the locking lug end from the locking position when a line of matrices of normal length is advanced to the assembling elevator, said lever being capable of swinging movement in excess of the movement required to withdraw the locking lug end from locking position, a second lock means actuated by excessive swinging movement of said lever and engageable with the projection, manually actuatable means carried by said bracket operable to hold said lever in position with the locking lug end thereof in inoperative position whereby when the detachable lug on the assembler slide is removed the machine can be used and operated in normal manner, said detachable lug being adjustable along the length of the assembler bar to set the stop mechanism to accommodate the assembly of lines of different lengths, and adjusting means on each of said stop means for minor adjustments of the parts.
